UNITED STATES PATENT OFFICE.

JOHN J. FRANK, OF PITTSFIELD, MASSACHUSETTS, ASSIGNOR TO GENERAL ELECTRIC COMPANY, A CORPORATION OF NEW YORK.

ELECTRICAL APPARATUS.

1,411,619.

Specification of Letters Patent.

Patented Apr. 4, 1922.

Application filed December 10, 1919. Serial No. 343,960.

To all whom it may concern:

Be it known that I, JOHN J. FRANK, a citizen of the United States, residing at Pittsfield, in the county of Berkshire, State of Massachusetts, have invented certain new and useful Improvements in Electrical Apparatus, of which the following is a specification.

My invention relates to electrical apparatus, and particularly to transformers, some reactances and the like. The object of my invention is to provide an improved arrangement of windings affording in combination better support, ventilation and magnetic balance than has been heretofore provided.

In accomplishing my invention I make use of a novel arrangement of supports for the windings and employ the novel manner of making connections between parts of the windings as is hereinafter set forth more fully in detail.

For a more complete understanding of the nature and objects of my invention reference should be had to the following detailed description taken in connection with the accompanying drawings in which:

Figure 1 shows in side elevation an arrangement of windings on a transformer embodying my invention. Fig. 2 is a perspective view showing a detail in the mode of connecting the windings according to my invention. Fig. 3 is a top plan view showing the arrangement for supporting the coils shown in Fig. 2. Figs. 4, 5 and 6 are views similar to Fig. 3 showing modifications.

Referring now to the drawings, 10 represents a magnetic core whose central leg supports the winding 11, of the interleaved disc-coil type.

The disc-coils 12 are wound on polygonal forms to give the contour shown, or they may be wound directly on the insulating cylinder 13 which surrounds the central leg of the core 10. When winding directly on the cylinder 13, the insulating devices, here shown as strips 14, which are equidistantly spaced about the cylindrical surface and are employed to support the coils in proper assembly, are used in the first instance as winding forms.

It is observed that the coils 12 so assembled about the cylinder 13, bear upon and are supported tangentially between the strips 14 by the cylindrical surface. Ventilating

ducts for admitting the circulation cooling medium, as oil or air for instance, are thus provided between the coils 12 and the cylinder 13 at each side of strips 14.

In disc-coil windings designed to carry relatively large currents, it is desirable to construct the coils so that the turns comprise a plurality of strands in parallel in order to insure that each part of the turn shall carry its proper proportion of the current. Each turn in the coils 12 shown in Figs. 2 and 3 comprises four such strands indicated respectively at 15, 16, 17 and 18. In order, therefore, to balance the magnetic side thrust occasioned at the point where the cross-over is brought out to go from one coil to another, I have here divided the strands into groups, groups of two being shown in Fig. 2, and bring out such groups at a plurality of symmetrically related points about the circumference of the coil. In Figs. 2 and 3 the groups are brought out at diametrically opposite points 20 and 21 in the circumference of the coils. In this manner the magnetic thrusts at the cross-overs on the outer circumference of the coils are balanced. The ordinary radial spacing strips for spacing the coils from each other or from insulating collars between the coils are shown at 19 in Fig. 3.

In Fig. 4 I have shown a coil of substantially similar form to that shown in Fig. 3, but instead of making the interior cross-over between coils at but one point as was indicated where the strands were shown at 15, 16, 17, 18, this inner cross-over is likewise made in a magnetically balanced manner. Accordingly the four strands are here divided into groups at equally spaced points about the inner circumference or periphery as at 30 and 31.

In Fig. 5, I have shown a coil in which the turn is composed of six strands. This lends itself readily to the dividing of the strands into three groups as shown at 40, 41 and 42. These points are equally spaced about the outer periphery of the coil in order to fully balance the magnetic forces about these cross-overs.

Similarly I have shown in Fig. 6 a coil having a turn composed of eight strands, divided into four groups 50, 51, 52 and 53 which are brought out at four equidistantly spaced points in order to balance the magnetic forces about them.

A transformer, or like induction apparatus, when built in accordance with my invention is accordingly relieved of a great amount of side thrust upon the coils, due to 5 the balanced arrangement for making cross-overs. Moreover the coils themselves have a very rugged support due to the tangential bearing of the turns on the inner insulating cylinder so that they are particularly able 10 to stand side thrusts and yet have ample interior ventilating capacity. My invention is consequently specially adapted to withstand hard service where short-circuits and the like frequently occur.

15 Having now described what is at present the best means known to me for carrying out an embodiment of my invention, I would have it understood that such means are merely illustrative and that I do not mean 20 to be limited thereby to the exact details shown nor in the choice of recognized equivalents except as defined in my claims hereunto appended.

What I claim as new and desire to secure 25 by Letters Patent of the United States, is:—

1. In an electrical apparatus, the combination with a winding composed of stranded turns adapted to be connected in parallel, of an insulating supporting surface on which 30 said winding bears tangentially at a plurality of points, said winding having its strands grouped and led off at equidistantly spaced

points to provide magnetically balanced cross-over connections.

2. In an electrical apparatus, a winding 35 composed of stranded disc-coils having their strands parallel connected and grouped and led off in equal numbers at equidistantly spaced points about the peripheries of said disc-coils to form magnetically balanced 40 cross-over connections between coils.

3. In an electrical apparatus, the combination with a winding composed of disc-coils generally polygonal in form, of a supporting insulating cylinder, and spacing devices 45 inserted between said coils and said cylinder at the vertices of the polygon in such wise as to hold said coils in place and to permit the inner turn to bear tangentially upon said cylinder.

4. In an electrical apparatus, the combination with a magnetic core, of an insulating cylinder surrounding a leg of the same, and stranded polygonal disc-coil windings mounted about said cylinder and bearing 55 tangentially thereupon, said windings having their strands connected in parallel, grouped and led off in equal numbers at a plurality of equidistantly spaced points about a periphery thereof to provide magnetically balanced cross-over connections.

In witness whereof, I have hereunto set my hand this 5th day of Dec., 1919.

JOHN J. FRANK.
